VARIABLE PAPER FEEDING MECHANISM
FOR ACCOUNTING MACHINESWalter A. Anderson, Bridgeport, Conn., assignor
to Underwood Elliott Fisher Company, New
York, N. Y., a corporation of Delaware

Application June 26, 1940, Serial No. 342,546

2 Claims. (Cl. 197—114)

This invention relates to accounting machines, and more particularly to improvements in a platen feeding mechanism for the paper carriages thereof.

It is often desirable to use accounting machines for printing single entry amounts on a continuous series of forms such as for example, checks. On such occasions, efficient machine operation requires automatic multiple line space advancement of the platen instead of its usual single line space advancement in order that the printing line of each form be moved into printing position immediately after the printing on a preceding form.

A paper feed mechanism of this character is disclosed in U. S. Patent No. 2,027,572, issued to me on January 14, 1936. In this disclosure, reliance is placed upon the use of two gears of high ratio to obtain the amount of platen movement necessary to effect the desired multiple line space advancement of the forms. It has been found in practice that this arrangement is objectionable in that the gearing ratio develops considerable inertia in the platen, causing it to overthrow, with resultant inaccuracy in paper feeding operations. Also, adjustment of this mechanism from single to multiple line spacing presents difficulties when a quick shift from single to multiple line spacing, or vice versa, is desired.

It is accordingly an object of the present invention to provide a reliable paper feed mechanism optionally operable to effect either single or multiple line spacing of the platen, and that may be regulated to perform either of these operations by a simple adjustment of a lever.

A further object of the invention is to provide a paper feed mechanism which, when in normal position, permits free manual rotation of the platen.

Another object of the invention is to provide a device of this character which is comprised of relatively few and simple parts, and which may be easily assembled and are inexpensive to manufacture.

With these and incidental objects in view, the invention consists in certain novel features of construction and combinations of parts, the essential elements of which are set forth in appended claims, and a preferred embodiment of which is hereinafter described with reference to the drawings which accompany and form part of the specification.

In the drawings:

Figure 1 is a fragmental left side elevation of my improved paper feed mechanism showing its

connection to pertinent parts of an accounting machine, the parts being shown in normal position and adjusted for a multiple line space operation,

3 Figure 2 is a view similar to Figure 1 but with the parts adjusted to position for effecting a single line space and actuated to mid-cycle position,

10 Figure 3 is a view similar to Figure 2 but with the parts adjusted to effect a multiple line space operation, and

Figure 4 is a fragmental rear perspective of the paper feed actuating bail.

The invention is shown in connection with a 15 carriage and accounting machine of the general character disclosed in U. S. Patent No. 2,088,982, issued to Oscar J. Sundstrand on August 3, 1937.

Referring to Figure 1, the paper carriage 1 is supported for lateral movement upon rollers 2 20 in the machine frame 3. The carriage includes end plates such as 4 between which is mounted a platen 5 fixed on a shaft 6 journaled in plates 4. The left end of shaft 6 extends through the left plate 4 and carries a toothed ratchet wheel 7 fixed thereon. The means for rotating the ratchet wheel comprises an oscillating arm 8 mounted on shaft 6 between wheel 7 and plate 4. A pawl 11 pivoted on a stud 12 fixed on the arm is arranged to engage the teeth of wheel 7 during its clockwise and counter-clockwise strokes, and to be disengaged from the teeth at the end of the counter-clockwise stroke, in a manner to be later described.

The mechanism for oscillating arm 8 first 35 clockwise and then counter-clockwise during each cycle of the machine will now be described. A lever 13 pivoted in the machine frame at 14 is connected by a link and crank connection (not shown) to the main rock shaft of the machine, and through these connections, as disclosed in Patent No. 2,088,982 (lever 13 being the same as lever 19 therein), lever 13 rocks first counter-clockwise and then clockwise about 45° during each cycle of the machine. A link 15 is connected at its lower end by a pin 16 and slot 17 with lever 13. The upper end of the link is pivotally and slidably connected as at 18 (see also Figure 4) to a universal rod 21 of a paper feed actuating bail generally indicated at 22, connection 18 permitting lateral travel of the carriage. Bail 22 comprises end plates 23 and 24 connected by a tie rod 25 and rod 21. The bail is pivoted on studs 26 secured in rearwardly extending arms of carriage end plates 4. Secured on the upper end of link 15 is a plate 27 (Figure 4) which is

slotted to embrace a vertical flange 28 of a bracket 31 attached to the rear of the machine frame. Flange 28, cooperating with slotted plate 27, guides the vertical movement of link 15 and prevents lateral displacement of the latter during movement of the paper carriage.

The means for connecting link 15 for movement with lever 13 comprises a latch 32 similar to that disclosed in the above mentioned Patent No. 2,027,572. Latch 32 is pivoted at 33 to link 15, 10 and has a slot 34 similar to slot 17 in lever 18 that likewise embraces pin 16 which is fixed in lever 13. At the upper end of slot 34, however, is an angular opening 35 to receive pin 16. A spring 36, connected to link 15 at 37 and to latch 32 at 38, 15 normally tends to swing the latch in a direction to cause opening 35 to engage pin 16.

When the parts are in normal position, however, as shown in Figure 1, a stud 41 on lever 13 engages the right hand edge of the latch and 20 holds the latch against such movement. In this position, slot 34 and slot 17 are in parallel uniform alignment and are concentric with the axis 14. When, however, lever 13 starts to swing in a counter-clockwise direction at the beginning of 25 a machine cycle, a spring 42 connected to lever 15 and anchored to the machine frame, tends to draw the link downwardly.

Continuing counter-clockwise movement of lever 13 moves stud 41 away from the latch, permitting spring 36 to swing opening 35 into effective engagement with pin 16. Consequently, in the remainder of the counter-clockwise movement of lever 13, link 15 is positively pulled downwardly, and in the return or clockwise movement of lever 13, link 15 is positively thrust upwardly, thereby imparting an oscillatory movement to the paper feed actuating ball 22. As the lever 13 completes its return to initial position, stud 41 thrusts latch 32 to the left, disengaging opening 40 35 from effective position with pin 16.

The oscillatory movement of ball 22 is imparted to arm 8 through the following train of parts. A link 43 is pivoted at 44 to an extension of end plate 24 and is pivoted at 45 to one arm of a bell crank 46 pivoted at 47 on a bracket 48 fixed on plate 4. The opposite arm of bell crank 46 carries a pin 51 lying within a slot 52 in one end of a pitman 53. The opposite end of pitman 53 is pivoted on stud 12 adjacent pawl 11 on arm 8. A strong spring 54, connected between a stud 55 in the left end of the pitman and a flange 56 of a bracket 57 secured on plate 4, normally tensions the pitman toward the right, as viewed in Figure 1.

When the parts are in normal position, however, pin 51 bears against the left end of slot 52 and holds the pitman in its normal or left hand position against the tension of spring 54. In this position, pawl 11 is held out of engagement with the teeth of ratchet 7 against the tension of a spring 58 connected between the pawl and arm 8, by a projection 61 on the pawl striking against flange 56, as shown in Figure 1. Likewise, in this position, a projection 62 formed on arm 8 stops against flange 56.

Upon clockwise oscillation of ball 22 by the downward movement of link 15, as before described, link 43 rocks bell crank 46 clockwise on pivot 47, swinging pin 51 away from the left end of slot 52, thus permitting pitman 53 to move toward the right. At the beginning of this rightward movement, arm 8 swings clockwise about shaft 6 and, as projection 61 moves away from flange 56, pawl 11 engages the teeth of wheel 7 under tension of spring 58.

Upon counter-clockwise oscillation of ball 22, as link 15 moves upwardly, an exact reverse movement of these parts takes place, pin 51 again engaging the left end of slot 52 and pulling pitman 53 toward the left, back to the normal position shown in Figure 1. At the end of this leftward stroke, projection 61 again engages flange 56, withdrawing pawl 11 from engagement with the teeth of wheel 7. Shortly thereafter, projection 62 of arm 8 stops against flange 56 and prevents possible overthrow of the parts incident to the sudden leftward thrust of pitman 53.

Single line spacing

Means is provided to control the number of teeth over which pawl 11 will pass during the movement of pitman 53 in order to regulate line space movement of the paper. This means includes a lever 63 pivoted at 64 on plate 4. A pin 65 fixed on the lower end of the lever is arranged to be moved into either of two positions, and a spring pulled detent 66 cooperating with a pin 67 on the lever is arranged to hold the lever in either of its adjusted positions.

When the lever is moved from the position shown in Figure 1 to the position shown in Figure 2, pin 65 lies in the horizontal plane of a shoulder 68 formed on the lower edge of pitman 53. With the lever adjusted in such position, when the machine is cycled, as pitman 53 moves toward the right, shoulder 68 stops against pin 65, limiting the extent of its movement, this extent of movement being just sufficient to permit pawl 11 to engage one tooth of wheel 7, as shown in Figure 2. The elongated slot 52 in pitman 53 permits idle riding movement of pin 51 during such operations.

Upon the subsequent restoration of the parts during the last half of the cycle, as described in the foregoing, pawl 11 rotates platen 5 one line space before it is disengaged by projection 61 striking flange 56.

Multiple line spacing

In order to effect a multiple line space operation, it is only necessary for the operator to shift lever 63 from the position shown in Figure 2 to the position shown in Figure 1, moving pin 65 from the horizontal plane of shoulder 68 into the horizontal plane of a shoulder 71. Now, upon cycling the machine, pitman 53 is permitted to travel a considerable distance further to the right until shoulder 71 stops against pin 65, a declivity 59 in the left end of slot 52 permitting further but idle movement of pin 51 following the stopping of pitman 53. This distance of travel is sufficient to permit pawl 11 to pass over a number of teeth of wheel 7 (herein shown as six teeth in Figure 3) and engage the last tooth of said number. Consequently, upon restoration of the parts during the second half of the cycle, platen 5 is rotated a commensurate number of line spaces when pitman 53 moves toward the left.

At the completion of such operation, projection 61 again stops against flange 56 to withdraw pawl 11 from engagement with the ratchet teeth, and likewise projection 62 strikes the flange to prevent overthrow of pitman 53.

A spring held roller detent 72 pivoted at 73 on plate 4 engages the teeth of wheel 7 to hold the platen securely in advanced position.

It will be noted that at the end of each line space operation, or rather whenever the parts are in normal position as shown in Figure 1, pawl 11 is automatically disengaged from the

ratchet; hence, free manual rotation of the platen is permitted without the necessity of making any special adjustment to so disengage the pawl.

It will be also noted that if it is desired to change from single to multiple line spacing, or vice versa, it is only necessary to manipulate lever 63.

Preventing line spacing

Mechanism similar to that disclosed in Patent No. 2,027,572 is provided on this machine to prevent line spacing operations in certain of the columns. For this purpose (Figure 1) a slide 14 (similar to the slide 39 in the aforementioned patent) is mounted in the machine frame for horizontal transverse movement. On one end of the slide is a pin 15 which, in one position of slide 14, lies beneath a lug 16 on link 15. Slide 14 may be reciprocated by any preferred means, as, for example, that disclosed in the Sundstrand Patent No. 1,779,717, dated October 28, 1930.

When pin 15 lies beneath lug 16, as lever 13 swings in the counter-clockwise direction, lug 16 is detained by pin 15, and pin 16 moves down in the slots 17 and 34 past the opening 35 before the movement of stud 41 releases latch 32 to the action of spring 36; hence, link 15 is prevented from descending far enough to impart effective movement to pawl 11, and no feeding movement takes place. During such an operation, slots 17 and 34 being in parallel uniform alignment and concentric with the axis 14, pin 16 rides idly within the slots. Upon removal of pin 15 from beneath lug 16, the machine is ready to perform its usual line space operations in accordance with the adjustment of the regulating lever 63.

It has been found in practice that this general construction insures positive, uniform and constant multiple as well as single line spacing operations.

While the form of mechanism herein shown and described is admirably adapted to fulfill the objects primarily stated, it is to be understood

that it is not intended to confine the invention to the one form of embodiment herein disclosed, for it is susceptible of embodiment in various forms all coming within the scope of the claims which follow.

What is claimed is:

1. In a machine of the class described, a shaft, a platen thereon, and a line spacing mechanism therefor, including a ratchet wheel connected to the shaft, an arm pivoted on the shaft and carrying a pawl to cooperate with the ratchet wheel, an actuator having a constant advance and return movement, means, including a pitman, connected to the arm and to the actuator, means normally urging the pitman to follow the actuator in its advance movement to impart movement to the arm, shoulders on the pitman, spaced apart to determine different stopping positions for the pitman, and a manipulative stop movable into the path of either of the shoulders to arrest the advance movement of the pitman, to control the advance of the pawl.

2. In a machine of the class described, a shaft, a platen thereon, and a line spacing mechanism therefor, including a ratchet wheel connected to the shaft, an arm pivoted on the shaft, a pawl pivoted on the arm and adapted to engage the ratchet wheel, an actuator having a constant advance and return movement, a pin on the actuator, a pitman having an opening in one end embracing the pin, and being connected to the arm at the opposite end, means normally urging one end of the opening against the pin so that as the pin moves, during the advance movement of the actuator, a movement is imparted to the pitman, means for stopping the pitman at different points in its advance movement to stop the movement of the pawl with respect to the teeth of the ratchet wheel, said opening having a configuration to accommodate movement of the actuator for the portion of its advancing movement that follows the stopping of the pitman in its advanced position.

WALTER A. ANDERSON.
